UNITED STATES PATENT OFFICE.

WILLARD D. LAWRENCE AND FRANCIS A. HOPKINS, OF CHICAGO, ILLINOIS;
SAID HOPKINS ASSIGNOR TO SAID LAWRENCE.

OFFICE-DOOR INDICATOR.

SPECIFICATION forming part of Letters Patent No. 521,983, dated June 26, 1894.

Application filed March 7, 1894. Serial No. 502,723. (No model.)

To all whom it may concern:

Be it known that we, WILLARD D. LAWRENCE and FRANCIS A. HOPKINS, citizens of the United States, residing at Chicago, in the 5 county of Cook and State of Illinois, have invented certain new and useful Improvements in Office-Door Indicators, of which the following is a full, clear, and exact specification.

The invention relates to indicators or devices for use on office doors and other or analogous places, for indicating to callers when the occupant will return, or for giving other information.

It is often desirable to leave on the outer 15 door of the office or other place, a notice of some kind, giving the time that the occupant will return, but owing to the exigencies of business and the vandalic tendencies of the small boy the means for giving this notice 20 must be both permanent and easily adjusted to suit the facts in the particular case and proof against casual efforts to remove or disfigure it. And for like reasons it should also be such that it may not be readily tampered 25 with or altered by unauthorized persons. The former of these requisites necessitates that the device be of small dimensions since an object of huge dimensions permanently secured to the door would be unsightly and 30 objectionable.

One of the important objects of the invention therefore is to produce a device for the described purpose and having the requisites specified, which shall be of small dimensions.

35 Another object of the invention is to provide a device of the described nature, which shall be simple and cheap in a minimum degree.

With these ends in view the invention consists in certain features of novelty in the construction, combination and arrangement of parts hereinafter fully described with reference to the accompanying drawings and more particularly pointed out in the claims.

45 In the said drawings, Figure 1 is a face view of the improved device. Fig. 2 is a transverse section thereof taken on the line 2—2 Fig. 1. Fig. 3 is a detail face view indicating the manner of forming one of the parts hereinafter described. Fig. 4 is a detail face view of the spring hereinafter described, and Fig.

5 is a detail view showing a modification of the operating knob and its stem.

Like signs of reference indicate like parts throughout the several views. 55

In constructing a device according to our invention we employ a circular dial A which may be constructed of any suitable thin material such for instance, as celluloid, card board or thin metal and upon which, when 60 the device is to be used for giving information having reference to the time of day, the figures or other characters a are printed or otherwise formed near its outer edge. In order that this dial may be shielded from injury 65 and kept clean it is arranged under a plate B which is provided at its edge with an opening C so that the proper number or character a may be presented to view, the dial A being revolute. With a dial of such small dimensions however, it is impossible to indicate the 70 whole and the fractional hours thereon in figures sufficiently large to be discernable through an opening which would disclose only the particular hour or fractional hour which 75 it is desired to present to view. We therefore make the opening C of sufficient extent to disclose at least the whole hour and the fractional hours between it and the next whole hour, and instead of writing each fractional hour out in full, as for instance, "1.15" 80 or "1.30," we indicate the whole hours and divide up the spaces between each two into the requisite number of divisions either by putting in the small figures or characters as 85 indicated in the drawings, or by making a simple division mark as on an ordinary time piece dial; so that any one hour and the fractions of an hour between that hour and the next whole hour may be disclosed at one time 90 in the opening C. We have shown the hours divided into quarters as such division is usually sufficient to meet the exigencies of ordinary business. In order now that it may be determined which of the whole hours or the 95 divisional hours is referred to by the indicator, we provide the edge of the opening C with a fixed index or pointer D projecting thereto and terminating near the edge of the line in which the characters a are arranged. Thus it will be seen that should it be desired to indicate 1.30 o'clock for in-

100

stance, the dial would be turned until both the figure 1 and the number 30 appeared in the opening C with the number 30 directly opposite the index D. The face of the plate 5 B may have indicated thereon the words "Will return at" or any other suitable matter having reference to the matter contained on the dial. These words may be formed on the plate at any convenient place, but they are 10 preferably arranged over the upper side with the last word arranged adjacent to the index D so that in reading the inscription the attention is led directly to the index, and the purpose of the device and the information 15 which it is intended to convey will be readily understood. A further advantage of the fixed index D and rotary dial is that the index does not change its position with relation to the inscription and the hour indicated 20 is always at the same and a convenient place to be read on the face of the device.

The dial A may be rotated by means of a stem E passing downward through it and a perforation F in the plate B and being provided with an operating knob. This knob and stem may be conveniently and cheaply formed by stamping the same out of a flat plate G in the manner indicated in Fig. 3. The stem is produced by striking down a 25 tongue which is also indicated by the letter E in Fig. 3, and whose connected end terminates or joins with the plate near the center of the latter, the tongue being turned down at right angles as shown in Fig. 2; while the 30 knob is formed by striking upward two tab-like portions g whose detached ends may be slightly widened and bent toward each other as indicated in Fig. 1, so as to form a purchase for the thumb and finger.

40 The aperture or perforation F in plate B as already described is circular and of such diameter that the tongue or stem E will fit accurately therein with capability of rotation, but without freedom of other movement. 45 The opening in the dial A however, through which this stem passes, is complementary in shape to the stem so that the dial will be turned when the stem is rotated.

The plate B is preferably formed integrally 50 with a rim or side portion H in which the dial A fits, and to this rim H under the dial is secured a back or bottom plate I. This is conveniently accomplished by providing the rim H with a flange or seat h upon which the plate 55 I is seated, and then reaming the edges of the flange h over the edges of the plate I as shown at h', thus holding the plate I in place and forming a box-like device in which the dial A is housed and protected.

60 As a means of securing the device to the door or other surface on which it might be desired to locate it, the back plate I may be provided with a screw J, and this is preferably located eccentrically near one edge so 65 that the body of the device may be utilized as a lever for turning the screw up. Such arrangement of the screw will also avoid bend-

ing the bottom plate inward when the device is subjected to the requisite pressure for forcing the screw in.

In order that the dial may be held firmly in its adjustment without danger of being disarranged by the casual efforts of passers by, or by other unauthorized persons not familiar with the construction, the under side 70 of the plate G is provided with a pin or lug K which is adapted to engage in any one of a number of cavities or holes L formed in the plate B, and thus lock the stem E against rotation until the plate G has been raised or 75 drawn outward a sufficient distance to disengage the pin K, the holes L corresponding in number and relative arrangement to the characters on the dial A, so that whenever a character is directly opposite the index D the pin 80 K will be coincident with one of the holes L.

In order that the plate G with its knob and stem may be drawn out sufficiently to permit of this disengagement of the pin K and yet when released to again cause such pin to engage, we provide the end of the stem with some suitable spring which will draw the plate G normally inward or against the plate B. In order to accomplish this and at the same time hold the dial A flat against the underside of the plate B, we interpose the spring 90 between the under side of the dial and a suitable lug on the stem E. The spring preferably consists of a blade spring M having a slot m through which passes a split nib e on the lower end of the stem E, the prongs of the nib being bent in opposite directions after 95 passing through the spring.

The pin or lug K may be conveniently formed by striking down a small portion of 100 the plate G.

If desired the knob and its stem and lug K, may be constructed as shown in Fig. 5, and which consists of an ordinary casting g² from which projects a stem having a rounded portion N for fitting the orifice F and a prismatic portion n for passing through a complementary opening in the dial and having the spring M secured to its lower end in any suitable way.

Having thus described our invention, what 115 we claim as new therein, and desire to secure by Letters Patent, is—

1. A device for the purpose described having in combination a movable dial provided with characters, a plate arranged over said dial and having an opening adapted to expose at one time a number of the characters on said dial and the edge of said opening being provided with an inwardly projecting index pointing to said characters, substantially 120 as set forth.

2. A device for the purpose described having in combination a movable dial provided with characters indicating whole and fractional hours, and a plate arranged over said 130 dial and being provided with an opening of sufficient extent to expose to view at least one whole hour and the fractional hours between such whole hour and the next whole hour, and

said opening being provided with an index pointing to said characters, substantially as set forth.

3. A device for the purpose described having in combination a movable dial having characters indicated thereon, a plate covering said dial and having an opening for exposing some of said characters and said opening being provided with an index, a knob for turning said dial and means for checking the rotation of said knob, substantially as set forth.

4. A device for the purpose described having in combination a rotary dial provided with characters, a plate covering said dial and having an opening for exposing some of said characters and the edge of said opening being provided with an index, a plate having a knob for turning said dial, one of said plates being provided with a series of sockets or perforations corresponding to the characters on said dial and the other with a pin or lug for engaging in said perforations or sockets, substantially as set forth.

5. A device for the purpose described having in combination a movable dial provided with characters, a plate covering said dial and having an opening in the line of movement of said characters, a knob for moving said dial, the said plate and knob being provided the one with a series of perforations or sockets and the other with a pin or lug adapted to engage in said sockets, and a spring for causing said pin or lug to engage, substantially as set forth.

35 6. A device for the purpose described hav-

ing in combination a movable dial provided with characters, a plate arranged over said dial and having an opening arranged in the line of said characters, a knob having a stem depending through said first plate and dial, a spring on said stem adapted to draw it in one direction and bearing against said dial, the said plate and knob being provided the one with a lug and the other with a series of perforations or sockets in which said lug engages, substantially as set forth.

7. A device for the purpose described having in combination a face plate provided with an opening, a knob having a stem passing through said face plate, a spring secured on said stem, a dial arranged on said stem between said face plate and spring and having characters arranged to pass said opening, the said face plate and knob being provided the one with a series of perforations or sockets and the other with a pin or lug adapted to engage in said sockets, substantially as set forth.

8. A device for the purpose described having in combination a rotary dial provided with characters, a face plate over said dial having an opening to expose said characters, a plate G having the upset tabs or portions g forming a knob and the down turned tongue E forming a stem passing through said dial, substantially as set forth.
